PILE FABRIC AND METHOD FOR PRODUCING
THE SAME

Fritz Koch, Derby, Conn., assignor to Sidney Blumenthal & Co. Inc., New York, N. Y., a corporation of New York

Application March 14, 1940, Serial No. 323,867

15 Claims. (Cl. 139—397)

This invention relates to pile fabric and method and apparatus for producing the same, and has for an object to provide for the manufacture of cut V-pile fabric on the double shuttle principle in which certain of the ground warps are so woven with respect to the pile that the cut pile V's are held in position in the ground of the finished fabric against pushing or pulling out or dislodgment when the fabric is in use as, for instance, when it is serving as motor vehicle 10 upholstery.

Another object is to provide for the manufacture of such a fabric in which the pile V's are held in position in the ground without the use of extra threads such as stuffer or cover warps, and without the use of any cementitious binding material.

Another object is to provide for the manufacture of such a fabric in which ground warp threads are woven so as to overlie the bights of the pile V's and thereby secure the latter against dislodgment in use, as already indicated.

Another object is to provide for the manufacture of such a fabric in which ground warp threads are woven so as to overlie not only the bights of the pile V's but also other ground warp threads, and are looped under certain weft threads in order firmly to bind the pile V's into the ground and prevent their dislodgment from correct position when the fabric is in use.

Another object is to provide for the manufacture of such a fabric in which ground warp threads are woven in a zig-zag line so as to have portions which lie substantially in a weft-wise direction and overlie bights of the pile V's.

Another object is to provide for the manufacture of such a fabric in which ground warp threads are woven as just described and also underlie weft threads located intermediate the pile V's.

Another object is to provide for the manufacture of such a fabric in which ground warps are interwoven with relation to wefts, other ground warps and pile V's so as greatly to strengthen the fabric without reducing its flexibility.

Another object is to provide for the manufacture of such a fabric by a method involving a novel adaptation of the principle of leno weaving.

Another object is to provide for the manufacture of such a fabric through the provision of novel apparatus fitted to accomplish the above named objects in a loom operating on the double shuttle principle.

A further object consists in providing certain

improvements in the form, construction, material and arrangement of the fabric and apparatus elements, and in the steps followed in the method of production, whereby the above named and other objects may effectively be attained.

A practical embodiment of means for producing this fabric and embodiments of two such fabric weaves are represented in the accompanying drawings, in which

Fig. 1 represents a detail, largely diagrammatical, view of certain parts of weaving apparatus and yarn in position for accomplishing one step of the method or procedure of manufacture;

Fig. 2 represents a similar view with the parts 15 in another position;

Fig. 3 represents a similar view with the parts in a third position;

Fig. 4 represents a similar view with the parts in a fourth position;

Fig. 5 represents an enlarged detail back view of the fabric weave accomplished by the operations represented in Figs. 1 to 4 inclusive;

Fig. 6 represents a section taken in the plane of the line VI—VI of Fig. 5, looking in the direction of the arrows;

Fig. 7 represents a section taken in the plane of the line VII—VII of Fig. 5, looking in the direction of the arrows;

Fig. 8 represents a view similar to Fig. 5 but 30 showing a modified form of weave; and

Fig. 9 represents a section taken in the plane of the line IX—IX of Fig. 8, looking in the direction of the arrows.

It is well recognized in this art that cut V-pile 35 fabrics have important characteristic advantages that reside chiefly in the excellent pile coverage; in economy of pile material, which is frequently expensive; and in simplicity of weave. On the other hand there is an equally well recognized 40 disadvantage in this type of fabric as compared, for instance, with cut W-pile fabric, consisting in the fact that, especially when submitted to frictional wear as in the case of vehicle or furniture upholstery, the pile V's become disturbed in position, dislodged, and often entirely pushed or pulled out of the fabric ground. To overcome this disadvantage, the art long ago resorted to the inclusion in the fabric of extra ground warps which were called by various names such as stuffer warps or cover warps, and which served the purpose of binding and crowding the pile V's so as to cause them to retain their position in the fabric ground. This expedient, of course, involved large added expense in material, labor,

reduced speed of production, and manufacturing difficulties.

In recent years it has been proposed to obtain the desired result and an even better result by forsaking the employment of the extra threads to which reference has just been made, and anchoring the pile V's against disturbance, dislodgment, or pulling or pushing out of the fabric ground, by the application to the back of the fabric of a cementitious binding material, such, for instance, as rubber or pyroxylin; as set forth in United States Patent to Leonard L. Crabtree No. 2,007,078, dated July 2, 1935. This last named procedure has been eminently successful but it has, of course, involved a certain expense for material and labor relating to the application of the cementitious material.

According to my present invention, both the above named procedures for improving the cut V-pile fabric are eliminated, and the pile V's are firmly secured in position in the ground without the use of any extra threads or any cementitious binding agent. By the expedient of interweaving certain of the normal ground warps in a novel relationship to the other threads, I am able to accomplish this important function as well as to increase the general strength of the fabric and the resistance of its other warp and weft threads to displacement.

In the accompanying drawings which include representations of apparatus suitable for carrying out my invention there are shown, for the sake of clarity, only those parts to which reference need particularly be made, because the other associated parts are well understood by those versed in this branch of the art as to form, construction, arrangement and operation.

Referring to Figs. 1 to 4 inclusive, a pile yarn is denoted by 1 and is threaded through a heddle 2 which latter is connected to any suitable operating mechanism for the purpose of floating the pile back and forth between the upper and lower fabrics being woven on a double shuttle loom, and shedding the said pile yarn so that it will lie around alternate wefts or picks as the upper and lower shuttles are shot through the loom. It will be understood, of course, that a large number of such pile yarns are arranged across the loom to be operated in the same manner and that only a single one is here shown in order to avoid encumbering the drawings.

Upper and lower ground warps 3, 4 are threaded through heddles 5, 6, which latter are also connected with suitable actuating mechanism as is common practice in this art, to be shedded and interwoven with the weft threads in the usual manner for the formation of the grounds of the upper and lower fabrics being woven. As in the case of the pile yarn 1, it will here also be understood that these ground warps 3 and 4 are duplicated in large number across the loom for the formation of the fabric webs.

Two more ground warps 7, 8 are threaded through fixed heddles 9, 10. These ground warps 7, 8 are, however, also threaded through doup needles 11, 12 that may have the usual spring, rod and shaft, or other suitable connection for moving them in directions opposite to the motions imparted to them by their heddles 13, 14. The needles 11, 12 are preferably of the standard form commonly used in leno weaving and their arms 15, 16, 17, 18 lie between the members 19, 20, 21, 22 of the heddles 13, 14, which members are interlaced as is usual, through slots 23, 24, 25, 26.

The general mechanical construction of the parts to which reference has just been made is set forth in United States patent to Jacob Kauffmann No. 1,037,151, dated August 27, 1912, but my apparatus embodies a new form of heddle for the doup needles residing particularly in the fact that each heddle 13, 14 is designed and shaped for operative interconnection with both the upper and lower doup needles 11, 12, so as to intermittently actuate the needles against their connecting springs or other mechanism for the purpose of imparting the desired movements to the ground warps 7, 8 in the upper and lower fabrics and with respect to the pile yarn 1 that is being interwoven, as above indicated, with both grounds and floated therebetween.

In addition to the novelty in the form of the heddles 13, 14, they are also positioned in a novel arrangement with respect to the needles 11, 12, notably in that one needle has its head or eye through which the yarn passes extending downwardly, while the other needle has its head or eye extending upwardly, with the result that the heddles 13, 14 serve to pull one needle downwardly and the other needle upwardly at intervals to accomplish the desired weaving motions in both the upper and lower fabrics. So far as I know, no apparatus has previously been devised for performing leno movements or any variations or adaptations thereof in the upper and lower fabrics being woven in a double shuttle loom.

From the foregoing description, it will be clear that the ground warps 3 and 7 are intended to be shedded and interwoven in the upper fabric, and the ground warps 4 and 8 to be shedded and interwoven in the lower fabric, while the pile yarn 1 is shedded and interwoven with both upper and lower fabrics as is customary in double shuttle looms weaving pile materials. It should also be noted that, as will be observed, the pile yarn 1 is shown in the drawings so as to have a somewhat different appearance from the ground warps, and the ground warps 3, 4 have a somewhat different appearance from the ground warps 7, 8. This has been done to facilitate reading of the drawings wherein the yarns take different positions in the first four figures, and is not intended as an indication of any particular characteristic with respect to the material, or composition, or twist of the different yarns.

The movements of the parts to perform the weaving operation will now be described; and it will, at the outset, be seen that, in the positions represented by Fig. 1, the ground warps 3 and 7 are shedded in the upper fabric so that weft or pick 27 may be shot through by its shuttle in the usual way. Likewise, ground warps 4 and 8 and pile yarn 1 are shedded so as to permit the insertion of weft or pick 28 below warp 4 and above warp 8 and pile 1 in the lower fabric. Ground warp 3 lies in front of ground warp 7 and pile warp 1 lies in front of ground warp 8. All the threads or yarns pass between the doup needle heddles, being behind heddle 13 and in front of heddle 14.

Turning now to Fig. 2 which illustrates the next step in operation, it will be observed that heddle 14 has moved upwardly thus permitting doup needle 11 to be raised by its controlling mechanism and carry warp 7 into the top position in the upper shed in which it is bound more completely around pick 27. Heddle 6 has moved downwardly so as to carry warp 3 into the bottom position in the top shed and cause it to bind more completely around the top of pick 27.

Heddle 2 has been elevated so as to bring the pile 1 from the bottom position in the lower shed to the top position in the upper shed which causes it to form a V-bight around pick 28 and also to be shedded for the insertion of an additional pick 29 in the upper fabric between the pile and the warp 3. Along with the movements just described, the heddle 5 has been depressed to carry warp 4 into the bottom position in the lower shed, while heddle 13 has been elevated and moved doup needle 12 with warp 8 upwardly in front of warp 4 so as to form a lower shed for the insertion of a further pick 30. This last named movement of doup needle 12 not only brings warp 8 from a position in back of warp 4 to a position in front of the latter, but it also forms a covering bend over the pile bight lying underneath pick 28, as hereinabove mentioned, thus binding the said pile bight firmly in position against the said pick.

Fig. 3 illustrates the next step in the weaving operation, from which it will be seen that heddle 2 has moved downwardly so as to bring the pile to the bottom position of the lower shed and cause it to form a bight around the top of pick 29; while heddle 6 has moved upwardly to carry warp 3 into the top position of the upper shed and heddle 13 has brought doup needle 11 and warp 7 downwardly in front of warp 3 so as to form a holding bend over the pile bight formed around the top of pick 29 and serve to secure the bight in position. At this point another pick 31 is shot through the shed formed by warps 3 and 7 in the upper fabric. Contemporaneously with the movements just described, heddle 5 has carried warp 4 into the top position of the lower shed and doup needle 11 has carried warp 8 into the lower position, whereupon another pick 32 is shot through above the pile and warp 8 and below warp 4.

In the next step represented in Fig. 4, the heddle 6 has moved downwardly so as to bring warp 3 into the bottom position of the upper shed and cause it to bend around the top of pick 31, while heddle 2 has raised the pile into the top position of the top shed and heddle 13 has permitted doup needle 11 to be raised by its actuating mechanism and carry warp 7 upwardly in front of the pile; in which position a further pick 33 is shot through the shed above warp 3 and below the pile and warp 7. The last named upward movement of heddle 2 carrying the pile yarn has formed a pile bight around pick 32, and this bight has been covered by a bend in warp 8 owing to the elevation of doup needle 12 by heddle 14 which carries the needle upwardly in back of warp 4 as the latter is depressed by the downward movement of heddle 5, thus forming a shed for the insertion of an additional pick 34 between the warps 4 and 8.

As clearly appears from the drawings, and as already mentioned, the heddle 13 is in front of all the yarns or threads while the heddle 14 is in back of them. Hence, when the doup needle 11 is moved downwardly or the doup needle 12 moved upwardly by the heddle 13, the said needles and the warps 7 and 8 passing through the eyes thereof are carried in front of other yarns which they pass; and when the needles 11 and 12 are moved downwardly and upwardly by the heddle 14, they are carried in back of yarns or threads which they pass. This causes, in effect, a zigzag weaving or positioning of the warps 7 and 8 since they pass first to one side and then

to the other of the pile 1 and the warps 3 and 4 respectively. These movements produce an interweaving bearing some resemblance to a leno effect because the picks are shot through sheds formed between the warps and the pile, as already described and clearly shown in the drawing, and hold the warps 7 and 8 in the positions to which they have been brought by the doup needles 11, 12.

The movements hereinabove described and illustrated in Figs. 1 to 4 inclusive, represent the completion of one repeat of the weave, and it will be understood that, while I have described the operations as though all of the picks named were inserted consecutively, the actual operation will involve the simultaneous insertion of pairs of picks in the upper and lower fabrics. As the woven double fabric moves along in the loom it is severed into two cut pile fabrics by a knife which cuts the pile floats intermediate the upper and lower grounds, the construction, arrangement and operation of the knife being well understood in this industry and requiring no illustration or description. Although the pile in each of the severed fabrics now has the form of V's each of which is looped around only a single weft or pick, the said V's are firmly secured in position and against dislodgment or pushing or pulling out of the fabric grounds by the bends of the warps 7, 8 which have been manipulated by the doup needles and heddles as above set forth.

The arrangement of the threads in plan view is well shown in Fig. 5 which represents the top or back of the upper fabric as well as the bottom or back of the lower fabric, because both are alike. Assuming this view to show the top or back of the upper fabric, the numerals 1, 3 and 7 denote the pile and the upper shed ground warps to which reference has heretofore been made. The wefts or picks woven in one repeat of this fabric are given their previous numbers 27, 29, 31 and 33. Examination of this view will show that the pile 1 is looped around alternate picks 29, 33 etc.; that the ground warp 3 is interwoven with the picks, going over and under them in alternation as is usual; and that the ground warp 7, which has been manipulated by the doup needle 11 and the heddles 13, 14, passes under pick 27 in a warp-wise direction, then over pick 29 and the bight of pile 1 in substantially a weft-wise direction, although at an angle thereto; then under pick 31 in a warp-wise direction; then over pick 33 and the bight of pile 1 in an angular weft-wise direction which is similar but opposite to the angularity of the warp 7 when passing over pick 29 and bight of pile 1 just mentioned. This angular zigzag course of the warp 7 continues throughout the length of the fabric; and the just described arrangement of the threads or yarns 1, 3 and 7 is, of course, repeated in a weft-wise direction throughout the width of the fabric. It will also, of course, be understood that the pile 1 and the ground warps 4 and 8 have the same interwoven relationship in the lower fabric as the pile 1 and the ground warps 3 and 7 in the upper fabric.

The construction of the double fabric before the pile floats are severed is shown in section in Fig. 6 looking in a warp-wise direction, and in section in Fig. 7 looking in a weft-wise direction; from which figures, in addition to those previously described, the interweaving or interlacing and tying effect of the threads or yarns

will be evident, and from which it will be seen that the ground warps 7 and 8 not only overlie the pile bights so as to hold the V's in position after the floats have been severed, but also act to hold the other ground warps, wefts and the pile in correct relative contiguity as originally woven, thereby preventing undesirable displacement of any of the threads by movements in the plane of the fabric, which displacement, if it occurred, would tend to militate against the uniformity of the fabric.

As previously indicated, Figs. 1 to 4 inclusive of the drawings show only two ground warps, with the appropriate picks, for each fabric, upper and lower, and one pile which is interwoven with the two fabrics and floated therebetween. As also previously indicated, the fabric resulting from the interweaving of the said threads, with their necessary duplication in the other dents of the loom, is illustrated in Figs. 5, 6 and 7.

While such a fabric is practical, I feel that it will be desirable in most cases to include an additional ground warp for each dent of each fabric, upper and lower, in order to improve the balance and general construction of the fabric. This modification is illustrated in Figs. 8 and 9, in which an additional ground warp 35 is interwoven in the same way as the ground warp 3 in the upper fabric; and an additional ground warp 36 is interwoven in the same way as the ground warp 4 in the lower fabric. This provides a ground warp on each side of the pile running in a straight warp-wise direction, and the zigzag warps 7 and 8 which are actuated by the doup needles and their heddles so as to bind in the pile bights, span in their weft-wise extent the pile bights and the warps on each side thereof which, as just noted, are numbered 3 and 35 in the upper fabric, and 4 and 36 in the lower fabric.

The arrangement of heddles and other loom mechanism for interweaving these ground warps 35 and 36 is so well understood in the art that there is no call for illustrating or describing the same further than has been illustrated and described in connection with the operating mechanism for warps 3 and 4, it being sufficient to note that the warps 35 and 36 are interwoven like the warps 3 and 4, respectively, although they may, of course, be arranged so as to pass around each pick on opposite sides thereof, instead of on the same side as shown in Figs. 8 and 9, by mere adjustment of the shedding mechanism, which is well understood and common practice in this art. It should be added that these warps 35 and 36, if used, are not to be considered as extra or additional threads in the sense that the stuffer or cover warps hereinabove referred to were extra or additional threads; because this form of fabric illustrated in Figs. 8 and 9 contains no more warp threads than have customarily been used in V-pile fabrics that were not provided with stuffer or cover warps or the like. These warps 35 and 36 are merely for the purpose of improving the general construction or balance of the fabric in a way analogous to the interweaving of ground warps in known fabrics.

In both forms of fabric the securing of the pile V's in position is obtained, not by the employment of additional threads or of any anchoring or cementing application but, on the other hand, by the novel interweaving of one of the regular ground warps in each dent, thereby greatly economizing the operation as compared

with the use of extra threads or anchoring or cementitious material, while improving the characteristics of the fabric in several respects. On the other hand, it should be emphasized that this invention in its broad aspect is applicable not only to the weave constructions shown in the drawings, but also to various other forms of pile fabrics, the significant feature being that ground warp threads are interwoven so as to overlie pile bights and hold the bights in position, regardless of the particular arrangement of the bights or the number and form of interweaving of the other warp and weft threads.

It will be understood that various changes may be resorted to in the form, construction, arrangement, material, and composition of the various elements of the fabric and the apparatus, and in the steps followed in the method of production, without departing from the spirit and scope of this invention; and hence I do not intend to be limited to the details herein shown and described except as they may be included in the claims.

What I claim is:

1. A pile fabric comprising, ground warp threads, ground weft threads and pile tufts, certain of the warp threads being interwoven so as to extend angularly in a combined weft-wise and warp-wise direction over the bights of the pile tufts on the back of the fabric and to underlie weft threads intermediate the pile tufts.

2. A pile fabric comprising, ground warp threads, ground weft threads and pile tufts, certain of the warp threads being interwoven in a zigzag warp-wise course so as to overlie bights of the pile tufts and other warp threads on the back of the fabric and to underlie weft threads.

3. A pile fabric comprising, ground warp threads, ground weft threads and pile tufts, certain of the warp threads being interwoven in a zigzag warp-wise course so as to overlie bights of the pile tufts, other warp threads and certain weft threads on the back of the fabric and to underlie other weft threads.

4. A method of weaving pile fabric including; interweaving warp and weft threads to form a ground, interweaving pile threads in said ground, and interweaving certain warp threads so as to cause them to pass to and fro weft-wise across and over the bights of certain pile threads.

5. A method of weaving pile fabric including; interweaving warp and weft threads to form a ground, interweaving pile threads in said ground, and interweaving certain warp threads so as to cause them to pass to and fro weft-wise across and over the bights of certain pile threads and across certain other warp threads.

6. A method of weaving pile fabric including; interweaving warp and weft threads to form a ground, interweaving pile threads in said ground, and interweaving certain warp threads so as to cause them to pass to and fro weft-wise across and over the bights of certain pile threads and across certain other warp threads and underneath certain weft threads at points on both sides of the pile threads.

7. A method of weaving pile fabric including; interweaving warp and weft threads to form a ground, interweaving pile threads in said ground, and interweaving certain warp threads so as to cause them to pass to and fro weft-wise across and over the bights of certain pile threads and across certain other warp threads and underneath certain weft threads at points on both

sides of the pile threads and said other warp threads.

8. A method of weaving double pile fabric including; interweaving warp and weft threads to form upper and lower grounds, interweaving pile threads in both grounds and floating them between the grounds, and interweaving warp threads so as to extend angularly in a combined weft-wise and warp-wise direction over the pile threads on the backs of both grounds.

9. A method of weaving double pile fabric including; interweaving warp and weft threads to form upper and lower grounds, interweaving pile threads in both grounds and floating them between the grounds, and interweaving certain warp threads so as to cause them to pass to and fro weft-wise across certain pile threads.

10. A method of weaving double pile fabric including; interweaving warp and weft threads to form upper and lower grounds, interweaving pile threads in both grounds and floating them between the grounds, and interweaving certain warp threads so as to cause them to pass to and fro weft-wise across certain pile threads and certain other warp threads.

11. A method of weaving double pile fabric including; interweaving warp and weft threads to form upper and lower grounds, interweaving pile threads in both grounds and floating them between the grounds, and interweaving certain warp threads so as to cause them to pass to and fro weft-wise across certain pile threads and underneath certain weft threads at points on both sides of the pile threads.

12. A method of weaving double pile fabric including; interweaving warp and weft threads to form upper and lower grounds, interweaving pile threads in both grounds and floating them between the grounds, and interweaving certain

warp threads so as to cause them to pass to and fro weft-wise across certain pile threads and certain other warp threads and underneath certain weft threads at points on both sides of the pile threads and said other warp threads.

13. A method of weaving pile fabric including; shedding ground warps and inserting picks to form a ground, interweaving pile threads in said ground, intermittently shedding said pile threads with warp threads in the ground and cross-weaving certain warp threads with respect to other warp threads in the ground, whereby said cross-woven warp threads overlie the bights of the pile threads in the ground in a combined weft-wise and warp-wise direction.

14. A method of weaving double pile fabric including; shedding ground warps and inserting picks to form upper and lower grounds, floating a pile thread from one ground to the other, intermittently shedding said pile thread with one of the warp threads in each ground and cross-weaving a warp thread with respect to another warp thread in each ground, whereby said cross-woven warp threads overlie the bights of the pile thread in each ground in a combined weft-wise and warp-wise direction.

15. A method of weaving double pile fabric including; shedding ground warps and inserting picks to form upper and lower grounds, floating pile threads from one ground to the other, intermittently shedding said pile threads with warp threads in each ground and cross-weaving certain warp threads with respect to other warp threads in each ground, whereby said cross-woven warp threads overlie the bights of the pile threads in each ground in a combined weft-wise and warp-wise direction.

FRITZ KOCH.
